SLIDE FASTENED CLOSURE CONSTRUCTION
FOR SHEER GARMENTSMarjorie E. Murray, Meadville, Pa., assignor to
Talon, Inc., a corporation of Pennsylvania

Application June 20, 1940, Serial No. 341,547

5 Claims. (CL. 2—74)

This invention relates to garments and more particularly to dresses and the like made of thin, flimsy and sometimes sheer material. Examples of such materials are sheer silks, sheer cotton fabrics and some flimsy artificial silk materials, and the term "flimsy" as used herein and in the appended claims refers to that degree of limpness found in such materials as distinguished from the relatively stiffer materials such as used in men's trousers, woolen skirts, etc.

In recent years, many such dresses have been provided with slide-fastened side placket closures and the general object of this invention is to provide an improved slide-fastened placket construction for dresses and similar garments made from such sheer materials.

Most slide-fastened dress plackets are made with a covering pleat or flap formed by doubling over the edge of the garment material. This flap, usually about $\frac{3}{8}$ " to $\frac{1}{2}$ " wide, extends free over the metal parts of the slide fastener and more or less conceals the same from view. It is highly desirable that this flap be made of the same material as the dress and be relatively thin so that it will have the same appearance and degree of flexibility as the material of the dress. In the cases of dresses made from such flimsy materials as mentioned above, great difficulty has been experienced due to catching of the material of the flap in the slider of the slide fastener when it is moved up or down. This catching of the flap material in the slider is due to the buckling and feeding in of the flimsy material between the slider and the interlocking fastener members. In the use of the most common types of sliders, this most often occurs by the material feeding in sideways at the outer corners of the wide end of the slider when the slider is being moved in a direction to close the fastener. When this flap material is thus caught in the slider it is a very serious matter. After the slider once catches the material, the more the wearer pulls on the slider the more the flap material wedges and feeds in under the slider. Unless great care is taken when the material is first caught, to feed the slider back, the slider is very likely to become so badly jammed that the fastener can neither be opened nor closed, thus rendering the dress to all intents and purposes, useless. Earlier efforts to prevent the flap material from catching in the slider have involved the use of linings or reinforcing layers of material in the flap construction. These have been only partially successful due to the cost and relative

stiffness and change in the appearance resulting from their use.

My invention provides a greatly improved placket construction which, without stiffening and changing the appearance of the covering flap, nevertheless prevents the material of the flap, even though very limp or flimsy, from catching in the slider of the slide fastener.

A further object of my invention is the overcoming of the above difficulties with the slightest possible increase in cost over former constructions.

Still another object of the invention is to provide an improved placket construction which will require no additional material or labor on the part of a dress manufacturer, and which will actually facilitate the attachment of a slide fastener in a placket opening.

In general my invention embodies a simple and efficient guard member which functions to lift the flap out of the way of the slider as the slider progressively moves along the fastener. Not only does this guard member tend to lift the flap out of the way of the slider, but serves effectively to block off the entrance to the slider channel. Thus even though the flap is held down against the fastener by some outside force, it will not be allowed to feed into the mouth of the slider and cause jamming of the fastener.

Other objects and advantages of the invention will hereinafter more fully appear.

In the accompanying drawing, I have shown for purposes of illustration, two embodiments which my invention may assume in practice. In this drawing:

Fig. 1 is a view, in perspective, of a dress embodying a slide-fastened placket constructed according to this invention;

Fig. 2 is a perspective view illustrating the catching of the flap material in the slider as in former placket constructions;

Fig. 3 is a fragmentary enlarged view of a portion of the placket illustrated in Fig. 1;

Fig. 4 is an enlarged section taken substantially on the line 4—4 of Fig. 3;

Fig. 5 is an enlarged fragmentary view, in perspective and partly in section, of the structure shown in Fig. 3; and

Fig. 6 is a cross-sectional view of a modified form of placket construction embodying my invention.

Referring to the drawing in detail and with reference particularly to Fig. 1, the garment shown is of flimsy or limp and usually sheer

material and comprises the front waist panel 10 and back waist panel 11 connected at the sides by seams 12 and connected at their lower ends by the waist seam 14 to the front skirt panel 16 and back skirt panel 17. The front skirt panel 16 and back skirt panel 17 are connected at the sides by seams 15. The side skirt seams 15 are mere continuations of the side waist seams 12 and garment is provided with conventional sleeves 18 and collar 19, of desired form.

The side placket opening extends upwardly and downwardly at each side of the waist seam 14 into the side waist seam 12 and side skirt seam 15 and a slide fastener, generally designated 20, is attached to the garment material on opposite sides of the opening. The slide fastener is covered by the flap or pleat 21 which is formed by doubling over the edge of the thin material of the front waist panel 10 and front skirt panel 16.

The details of the placket construction of the garment of Fig. 1 are shown in Figs. 3, 4, and 5. The slide fastener includes stringer tapes 22 and 23 provided with adjacent reinforced edges 24 and 25 respectively, upon which reinforced edges are secured rows of complementary interlocking fastener members 26. Conventional top and bottom stops (not shown) may, of course, be included.

A slider 27 is provided with a pull tab 28, by means of which it may be manually moved, longitudinally of the rows of interlocking fastener members 26, upon which it is supported, for progressively engaging and disengaging the interlocking fastener members 26 of the respective rows to open and close the fastener.

In accordance with the construction of such sliders they comprise top and bottom wings connected by a narrow neck at one end providing between the wings a Y-shaped channel. The wings have preferably curved-shaped side flanges 21a and it will be observed that the outside corners 21b of the slider at its wide end are so shaped that they tend to gather in any flimsy material which might be in their path. This is especially true in view of the fact that the fastener members 26 must fit loosely in the entrances or mouths of the slider channels. The action of the slider catching in the flimsy flap material is shown in Fig. 2.

In attaching the slide fastener in the placket opening which extends, as above described, into the lower portion of the side waist seam 12 and into the upper portion of the side skirt seam 15, the joined edge portions of the back waist panel 11 and the back skirt panel 17 are folded over upon themselves, as shown at 11a in Fig. 4, to form a double ply edge portion. This double ply edge portion is secured by a row of stitching 29 directly to the stringer tape 23 of the slide fastener. The joined edge portions of the front waist panel 10 and the front skirt panel 16 are likewise overlapped upon themselves to form a relatively wider double ply edge portion, as shown at 10a which constitutes the above-described fastener covering pleat or flap 21. This double ply edge portion which forms the pleat or flap 21 is secured by a row of stitching 30 to the fastener stringer tape 22, as shown in Figs. 2, 3 and 4. This, above-described, structure is sometimes known as the knife pleat placket.

The illustrated embodiment of the flap-guarding means and lifting means comprises the longitudinal cord 32 which is secured to the stringer tape 22 by means of a line of stitching 31. The

guard member 32 is located between the stitching 30 (defining the line of attachment of the flap or pleat 21 and the fastener stringer tape 22) and the row of fastener members on the tape 22.

5 The size and shape of the cord 32 may be varied within reasonable limits but preferably it is sufficiently large that it extends above the fastener tape 22 a slightly greater distance than the fastener members 26. The size and location of 10 this cord and the location of the stitching 30 is such that the cord is spaced from the fastener members only enough to allow the slider flanges to ride between the fastener members and cord. This spacing, for example, may be about $\frac{1}{8}$ of an 15 inch or less. The cord is also arranged very close to the stitching 30. The curve in the side of the slider compels the cord alongside the slider to assume almost the same curve, and due to a certain degree of stiffness of such a cord the curve 20 extends beyond the wide end of the slider. The pushing sidewise of the cord by the slider, especially beyond the wide end of the slider, causes the flap to be lifted up in the region of the fastener. In other regions the flimsy flap material 25 will easily bend over the cord and normally lie quite close to the fastener members so as to conceal them from view. The proportions of the member 32 are thus such that it fits snugly into the crotch between the flap or pleat 21 and a 30 stringer tape 22, while at the same time preferably engaging the widest portion of the slider 27 at its upper end, as shown in Fig. 3.

Furthermore, as shown in Fig. 3, upward movement of the slider is accompanied by progressive 35 movement of the guard member 32 outwardly transversely of the closure opening, in advance of the slider. The snug fitting of the guard member 32 in the crotch between the flap or pleat 21 and the stringer tape 22, causes the overlying flap 40 or pleat 21 also to be moved forwardly and transversely outwardly of the closure opening because of the outward thrust exerted upon the flap or pleat 21 by the underlying guard member 32, which is so moved away from the path of the 45 slider.

The application of the principles of this invention to a "double knife pleat" or "box pleat" slide fastener closure construction is illustrated in Fig. 6. As shown in Fig. 6, the joined edge portions 50 of the front waist panel 10 and front skirt panel 16 are folded over upon themselves, as shown at 16b, to form a two-ply pleat or flap 40 terminating substantially midway of the width of the fastener. The joined edge portions of the back 55 waist panel 11 and back skirt panel 17 are likewise folded over upon themselves, as shown at 11b, to form a similar pleat or flap 41 adapted to abut the above-described pleat or flap 40 substantially midway of the width of the fastener. The 60 fastener stringer tape 22 is secured to the overlying pleat or flap 40 by the stitching 30, while the other slide fastener stringer tape 23 is secured in like manner by the stitching 31 to the double ply pleat or flap 41.

65 Attached to each of the stringer tapes 22 and 23 at the crotch between the stringer tapes 22 and 23 and the overlying attached pleats or flaps 40 and 41 are guard members or lifting members 70 comprising flexible cords 32 which are secured to the stringer tapes 22 and 23 by stitching 31. These cords 32 are located concentrically with respect to the slider, in such spaced relation as described above, so that the widest portion of the slider progressively moves outwardly the cords 75 32 at each side thereof when the slider 27 is

moved upwardly with respect to the stringer tapes 21 and 23 and the attached interlocking fastener members 26.

Upon upward movement of the slider with respect to the closure construction, the cords 32 progressively block the critical outer corner portions of the slider mouth openings, and while being moved both outwardly transversely of the closure opening, progressively thrusting the overlying pleats or flaps 40 and 41 upwardly and outwardly away from the path of the slider for effectively preventing the feeding of the sheer material of the pleats or flaps 40 and 41, either into the space between the interlocking fastener members 26, in advance of the slider, or between the slider and the interlocking fastener members 26 at the upper mouth portions of the slider.

It will be observed that the cord or cords may be attached to the slide fastener by the fastener manufacturer, requiring no additional material or labor on the part of the garment manufacturer. There is actually an important advantage to the dress manufacturer because the cord or cords help to locate accurately the stitching which secures the slide fastener in position, making the lines of stitching straighter and more uniformly spaced from the fastener members.

From the above description, it will clearly appear that I have provided a slide-fastener closure construction for garments of sheer and flimsy material which embodies means effectively preventing catching of the fastener covering flap or pleat.

My invention although embodying only the use of flexible cords or their equivalent which are relatively cheap in themselves and relatively cheap to attach a slide fastener, makes it practically impossible for anyone to catch the flap material in the slider and jam the fastener. It not only causes the flap material to be lifted out of the way of the slider during movement of the slider along the fastener, but effectively blocks the entrance to the corners of the slider where the material feeds in so that even if the flap accidentally falls or is held down against the fastener, it will not catch in the slider. At the same time, this flap remains flimsy and in the case of thin transparent materials, it still has the same thin transparent appearance and flexibility, thus carrying out the sheer effect of the dress material.

It is, of course, to be understood that the above description is merely illustrative and in nowise limiting and that I desire to comprehend within my invention such modifications as are included within the scope of the appended claims.

Having thus fully described my invention, what I claim as new and desire to secure by Letters Patent is:

1. In a dress or the like of flimsy material having a side placket opening, a slide fastener for closing the opening including a pair of stringer tapes attached directly to the garment material on opposite sides of the opening, rows of interlocking fastener members on adjacent edges of the tapes, and a slider movable on the fastener members for opening and closing the fastener, a covering flap formed wholly of the same flimsy material as the dress attached to the garment material on one side of the opening and overlying the fastener members, and a cord-like member extending along the rows of fastener members substantially the entire length of the slide fastener and attached only to the stringer

tape on that side of the opening to which the flap is attached and located between the rows of fastener members and the line of attachment of such stringer tape to the garment material, to prevent the flimsy flap material from catching in the slider as the slider is moved along the fastener members.

2. In a dress or the like of flimsy material having a side placket opening, a slide fastener for closing the opening including a pair of stringer tapes attached directly to the garment material on opposite sides of the opening, rows of interlocking fastener members on adjacent edges of the tapes, and a slider movable on the fastener members for opening and closing the fastener, a covering flap comprising an integral extension of the same flimsy material of which the dress is made folded under so that the flap consists of two thicknesses of such material, such flap extending over the rows of fastener members, and a cord-like member extending along the rows of fastener members substantially the entire length of the slide fastener and attached only to the stringer tape on that side of the opening to which the flap is attached and located between the rows of fastener members and the line of attachment of such stringer tape to the garment material, to prevent the flimsy flap material from catching in the slider as the slider is moved along the fastener members.

3. In a dress or the like of flimsy material having a side placket opening, a slide fastener for closing the opening including a pair of stringer tapes attached directly to the garment material on opposite sides of the opening, rows of interlocking fastener members on adjacent edges of the tapes, and a slider movable on the fastener members for opening and closing the fastener, a covering flap formed wholly of the same flimsy material as the dress attached to the garment material on one side of the opening and overlying the fastener members, and a guard member to prevent the flimsy flap material from catching in the slider as the slider is moved along the fastener members, said guard member comprising a cord positioned between the flap and the adjacent fastener tape, said cord being spaced from the rows of fastener members only sufficiently to permit free sliding movement of the slider, and said cord being attached only to the stringer tape by a line of stitching extending through the cord and tape.

4. In a dress or the like of flimsy sheer material having a side placket opening, a slide fastener for closing the opening including a pair of stringer tapes, rows of interlocking fastener members on adjacent edges of the tapes, and a slider movable on the fastener members for opening and closing the fastener, a covering flap consisting of an integral extension of the dress material on one side of the opening folded under so that the flap consists of two thicknesses of the dress material, lines of stitching attaching the fastener tapes directly to the dress material on opposite sides of the opening, the line of stitching on the flap side extending through the folded under portion of the flap and a cord positioned between the flap and adjacent fastener tape arranged between said last mentioned line of stitching and the adjacent row of fastener members, said cord being located closely adjacent said line of stitching and also closely adjacent the row of fastener members and connected only to the stringer tape whereby it is contacted by the slider as the slider moves along the fas-

tener members to cause the flap to be pushed upwardly away from the slider as the slider is moved along the fastener.

5. In a garment of sheer flimsy material having an opening, a slide fastener for closing the opening including a pair of stringer tapes attached directly to the garment material on opposite sides of the opening, rows of interlocking fastener members on adjacent edges of the tapes and a slider movable on the fastener members for opening and closing the fastener, a flap formed as an integral extension of the flimsy sheer material on one side of the opening and extending at least partially across the rows of fastener members and a cord-like guard member extending along the rows of fastener mem- 10
15

bers substantially the entire length of the opening and secured in position between said flap and the adjacent stringer tape, the thickness of the cord-like guard member being substantially greater than the distance which said fastener members project above the flat surface of the stringer tapes, said guard member being attached only to the tape in a position spaced only slightly from the adjacent row of fastener members, whereby the guard member blocks the entrances to the slider along the adjacent side and at the adjacent corners of the slider to prevent the flimsy flap material from catching in the slider as the slider is moved along the fastener members.

MARJORIE E. MURRAY.
